DRAFTING INSTRUMENT.

Application filed July 25, 1925. Serial No. 45,967.

This invention relates to drafting instruments and particularly to triangles. The principal object of the invention is to provide a new and improved construction of a triangle, particularly designed and adapted for use by draftsmen for drawing lines to be used as guides for lettering. Considered more specifically the invention consists in the construction of a triangle provided with 5 a plurality of through holes arranged in a series of sets; the holes in each of said sets being spaced from each other at the required proper distances to correspond to the height and the spacing for capital and lower case 10 standard letters. Each set of holes is preferably inclined to both of the longer sides of the triangle, and the spaces between the holes are so arranged that when the triangle is placed with one of the sides against a 15 straight edge, a T square or the like, the resulting guide lines drawn with such side as a base line will be spaced the proper distance for letters of a given predetermined dimension; while when the other longer side 20 of the triangle is used as the base line the guiding lines drawn for this latter position will correspond to the proper spacing for letters of a different height.

The above objects and other objects of the 25 invention will be apparent to those skilled in the art to which the invention relates from the following more detailed description and by reference to the accompanying drawings forming a part hereof and wherein Fig. 1 of the drawing is a plan view showing a triangle, constructed in accordance with the 30 principles of my invention; the figure illustrating the arrangement of the holes and some of the lines which may be drawn when 35 the hypotenuse of the triangle is used as the base line; Fig. 2 is a view similar to Fig. 1 showing some of the lines which may be drawn when the longer straight side of the triangle is used as a base line; the short dot 40 and dash lines appearing at the left-hand side of the figure corresponding to the lines drawn in Fig. 1, and Fig. 3 is a cross-sectional detail of the holes of the triangle.

As will be seen from Figs. 1 and 2 of the 45 drawing, four sets of holes A, B, C and D are preferably provided; the holes of each set being spaced from each other at different predetermined distances as will be herein- 50 after more fully set forth. Each of the holes 55 provided in the triangle is preferably coun-

tersunk as shown at *a* in Fig. 3 to facilitate the insertion of a sharp pointed pencil *b*; the holes being counter-sunk on one side only, as clearly shown in said figure. The upper or counter-sunk face of the triangle 60 has impressed or otherwise suitably placed thereon, suitable numerals or other indicia, for convenience in identifying the spacing of the holes of each particular set. In the particular example herein illustrated it will 65 be noted that the longer straight or 8" side of the triangle is provided with the numerals 3, 5 and 7 adjacent to the sets of holes A, B, C respectively, and also with the numerals .15, .25, .35, at the bases of these sets 70 respectively, while the set of holes D has adjacent thereto, the numeral .10. On the hypotenuse side, the sets of holes A, B, and C, are numbered 4, 6, 8, and .20, .30, .40, respectively, while the set D is numbered 75 .125. The numerals 3 5 and 7 indicate the distance between the guide lines drawn for capital and lower case long letters when the 8" side of the triangle is used as the base line, and such distances in the example 80 illustrated are respectively $\frac{3}{2}''$, $\frac{5}{2}''$, $\frac{7}{2}''$, while the numerals .15, .25, .35, indicate in decimals of an inch the distance between the guide lines for standard block lettering. The numerals 4, 6 and 8 also indicate in 85 thirty seconds of an inch, and the numerals .20, .30, .40, and .125, the distances in decimals of an inch when the hypotenuse side of the triangle is used as the base for the drawing of guide lines. The distances represented by the decimals correspond to the 90 proper heights for standard block lettering and for the proper spacing for consecutive rows thereof.

The holes of each of the sets A, B and C 95 are arranged to form groups, which groups in the set A consists of three holes each and in the sets B and C of four holes each. It will be noted that in each respective set the holes are similarly arranged in each group, 100 that each group is spaced equally from an adjacent group and that the similarly located holes of each group of each set are arranged along lines parallel to each other and inclined differently with respect to both 105 the longer side and the hypotenuse, the holes being so located, as clearly shown, that they form three parallel rows in each set. In each set, the inclination of these rows, the spacing of the holes in each row, and the 110

relative position of the holes in each row to the holes in the other rows are so arranged that the distances from the lower to the upper hole of each group, measured along the perpendiculars to the longer side and to the hypotenuse respectively, correspond to the proper heights for standard capitals and lower case long letters, the distances from the lower hole to the middle hole of each group correspond to the proper heights for standard lower case short letters, while the distances from the lower hole of a group to the lower hole of the group immediately above it correspond to the proper heights for standard block letters. As the angle between the parallel rows of each set of holes and the 8" side and the hypotenuse respectively, of the triangle is different, the distances between the guide lines drawn, when the straight side and the hypotenuse are used, will obviously be different. This angle of inclination is however selected so as to secure the relationship described above for the spacing of the letters and is determined by the standard spacing for various types of lettering and the angle between the two reference sides of the instrument.

It will be noted that the holes of set A are grouped differently from the holes of the sets B, C, the former being open spaced and consisting of a plurality of groups, each of which consists of three holes arranged in parallel lines inclined at a definite predetermined angle to the 8" side and to the hypotenuse of the triangle. This angle may be readily determined from the formula

$$\frac{A}{B} = \frac{\sin X}{\sin Y} = \frac{\sin X}{\sin X - Z}$$

in which A = spacing referred to the 8" side of the triangle.

B = spacing referred to the hypotenuse.

X = angle between the inclined line of the holes and the A reference side.

Y = angle between the line and the B reference side.

Z = the angle between the 8" side and the hypotenuse of the triangle.

It will be understood, that the arrangement or grouping of holes used for the set A, could be employed throughout but in order to save space and keep each set of holes distinctly separated from the others, the grouping of the sets B and C is also employed. With the latter grouping although only three holes are used together for each reference side of the triangle, each grouping really consists of four holes but for N groups only 3 N + 1 holes are needed, as clearly shown in the drawings, so that one hole of each group of four holes is common to two groups. In other words, considering the set of holes C the fourth hole from the bottom in Fig. 1 is the bottom hole of the second group from the bottom and is used with the

two holes immediately above it for drawing the lines for the letters D, d, shown at the left of said figure. When the triangle is reversed to the position of Fig. 2 the hole, which was in Fig. 1, the fourth hole from the bottom becomes the fourth hole from the top and it is now used with two different holes as the bottom hole of a different group, to draw the differently spaced lines for the letters A, a of Fig. 2. The cut-out portion E of the triangle has the sides thereof inclined at an angle of 67½° from either reference edge, to correspond with the standard slope or inclination for various types of lettering.

The manner in which the instrument is used is as follows: Assuming that it is desired, for example, to draw letters having a height of $\frac{3}{2}$ " for capitals and long letters, the draftsman would place the hypotenuse of the triangle against his T square or other guiding surface and, placing his pencil successively within the three holes forming the lower group of holes of set C, and sliding the pencil and triangle along the T square, would draw the lines between which the letters E, e, appear at the left-hand side of Fig. 1. If it is desired to make consecutive rows of lettering, the next group of three holes are used, and the lines drawn, at which the letters D, d appear at the left-hand side of Fig. 1. It will be noted that starting either from the top or bottom, the distance between the upper and lower hole of each group of the holes of set C, which are indicated as having been used in Fig. 1, is $\frac{3}{2}$ ", while the distance between the lower hole of each group of three and the intermediate hole is $\frac{5}{8}$ of this or $\frac{3}{2}$ ", the proper height of the body of lower case letters, and the distance between the upper hole of each group of three and the lower hole of the adjacent group of three, is also about $\frac{3}{2}$ ".

The lines drawn in Fig. 2 illustrate how the spacing between the lines differs for each particular set of holes when the longer, or 8", straight side of the triangle is used as a base for drawing the guide lines; the full lines having been drawn with the holes of set C, the same as were used for the drawing of the lines of Fig. 1, while the dot and dash lines indicate the spacing of the lines of Fig. 1. The lines of Fig. 2 are $\frac{7}{2}$ " apart for capital letters and $\frac{5}{8}$ of this for the body of lower case letters, while the distance between consecutive rows of letters is .35", as indicated by the numerals on the face of the triangle. If full capital letters are to be drawn the centre line of holes are employed; the lines extended to the right of Figs. 1 and 2 and having the letters E, F, G at the ends thereof illustrating the spacing.

It will be seen that guide lines may be drawn for five rows of lower case letters or three rows of capital letters, with the proper

spaces between the rows, for each group of holes without shifting the straight edge. It will also be seen that by arranging the holes at a predetermined angle of inclination with respect to the hypotenuse and the 8" side of the triangle, and by spacing the holes of each group in the manner indicated, that I am enabled to double the range of the instrument and to obtain with a relatively small number of holes practically all of the standard spacings commonly used in practice.

While I have shown and described the triangle as having an 8" side, it will be understood that the triangle may be made of any dimensions, the 30°, 60° type and 8" dimension being given merely as illustrative of and not as limiting the invention. It will also be understood that the number of groups of holes may be varied and that the distances between the holes of each particular group may also be varied from the illustrative example given without departing from the principles of my invention.

It will further be understood that the principles of construction herein disclosed are not limited in their application to a 60° triangle as shown, nor to an instrument having a triangular shape, but that the invention is capable of application to an instrument of any desired shape having a pair of sides inclined to each other.

I claim:

1. An instrument of the character described having a pair of straight sides inclined to each other at a predetermined angle and a body portion between said sides, said body portion being provided with a plurality of sets of holes, the holes of each set being arranged in parallel rows and forming a plurality of spaced groups, each of said groups consisting of an equal number of similarly spaced and arranged holes, and the rows of holes of each set being inclined at a different angle to said sides from those of the other sets, such angles being predetermined according to the angle between the sides and the standard heights for different sizes of lettering whereby spacing lines for different sized but similar style standard letters may be drawn with the holes of each set when different ones of said pair of sides are used as a base line.

2. An instrument of the character described having a pair of straight sides inclined to each other at a predetermined angle and a body portion located between said sides, said body portion being provided with a plurality of spaced holes arranged at predetermined distances from each other and forming a plurality of spaced sets, each of which consists of a plurality of rows of equally spaced groups of holes, the rows of holes of each set being so inclined at a different angle to each of said sides and the

spacing between the holes of each set being so arranged between the individual holes of each group that when spacing lines are drawn by the aid of such holes parallel to one of the sides of the instrument the distance between said lines will correspond to the proper spacing for consecutive rows and to the proper heights for standard letters, while when the same holes are employed for drawing lines parallel to the other side of the instrument the latter lines will correspond to the proper spacing for consecutive rows and to the proper heights for similar style standard letters of different dimensions.

3. A drafting triangle having the body portion thereof provided with a plurality of holes therethrough, in each of which the point of a pencil is adapted to be placed for drawing guide lines for standard lettering, said holes being arranged in sets of parallel spaced rows, the rows of each set being inclined at a different predetermined angle to each of the sides of the triangle according to the angle between the sides and the heights of different sized but similar style standard letters for which each set of holes is to be employed, the holes of each set being further spaced and arranged to form a plurality of groups in which said holes are so arranged that the distances between lines drawn parallel to either of the two sides by the use of certain holes of each group correspond to different proper heights for standard lower case high and low letters, the distances between each group of holes correspond to different standard spacing for consecutive rows of lower case letters and the distances between certain corresponding holes of adjacent groups corresponds to different proper heights and spacing for upper case standard letters according to which side of the triangle is used as a base.

4. A drafting triangle having the body portion thereof provided with a plurality of holes arranged in sets of three parallel rows inclined at different predetermined angles to two of the sides of the triangle according to the angle between said sides and the heights for different sized lower case standard lettering for which each set of rows is to be used, the holes in each of said rows being equally spaced from each other but at different distances than the holes of the other rows, and the holes of each of the rows of each set of rows being arranged in a definite predetermined relationship to the holes of the remaining rows of their respective set.

5. An instrument of the character described having a pair of straight sides inclined to each other with a body portion between said sides, said body portion being provided with a plurality of rows of equally

spaced holes, the angle between each respective row and each of said sides bearing a definite predetermined mathematical relationship to a different distance and to the angle between said pair of sides, each of said distances representing and being determined by the average height dimensions for lower case letters of different standard dimensions.

10 6. In a lettering triangle, the combination of a series of groups of guide line holes so disposed relative to two edges of the triangle that from either edge predetermined spacings for said guide lines may be drawn, and 15 a larger triangular hole two edges of which are so inclined to the two reference edges of the triangle that standard slope guide lines may be drawn therefrom.

7. An instrument of the character de-

scribed having a pair of straight sides inclined to each other at a predetermined angle with a body portion between said sides, said body portion being provided with a plurality of holes arranged in sets of parallel spaced rows, inclined at different angles to said sides predetermined according to the angles between said sides and standard lettering dimensions, the holes of certain of said sets being further arranged in groups in which the holes are similarly spaced with a terminal hole of each group common to an adjacent group, and the number of holes in the set being equal to $3N+1$ in which N equals the number of groups of holes in the particular set. 35

In testimony whereof I have hereunto set my hand.

WILLIE L. E. KEUFFEL.
